UNITED STATES PATENT OFFICE.

EMIL WEINER AND HARRY KATIMS, OF NEW YORK, N. Y.

DESIGN FOR A TEXTILE FABRIC.

Application filed February 1, 1928. Serial No. 25,132. Term of patent 3½ years.

To all whom it may concern:

Be it known, that we, EMIL WEINER and HARRY KATIMS, both citizens of the United States, residing at New York, in the county of New York and State of New York, have invented a new, original Design for a Textile Fabric, of which the following is a specification, reference being had to the accompanying drawings, forming part thereof.

The figure is a face view of a textile fabric showing our new design.

We claim:

The ornamental design for a textile fabric as shown.

In testimony whereof we have affixed our signatures.

EMIL WEINER.
HARRY KATIMS.
